UNITED STATES PATENT OFFICE.

JAMES BOLTON, OF GLEN SPEY, NEW YORK.

SHUTTLE-OPERATING MECHANISM FOR SEWING-MACHINES.

SPECIFICATION forming part of Letters Patent No. 367,021, dated July 26, 1887.

Application filed July 24, 1886. Serial No. 208,939. (No model.)

To all whom it may concern:

Be it known that I, JAMES BOLTON, a citizen of the United States, residing at Glen Spey, in the county of Sullivan and State of New York, 5 have invented certain new and useful Improvements in Shuttle-Operating Mechanisms for Sewing-Machines, of which the following is a specification, reference being had therein to the accompanying drawings.

10 My invention relates to that class of sewing-machines adapted to form lock-stitches by means of oscillating or rotating shuttles co-operating with the needles thereof, the object of my invention being to provide a clamping device by which the shuttle is held to the driver in such a manner that a race for the shuttle to run in will not be required, and the objectionable friction and wear incidental to running the shuttle in the race will thus be avoided.

15 My clamping device consists of a plate pivoted to and moving with the shuttle-driver, said plate having an opening or forked portion to receive a stationary cam by which the said plate is swung on its pivot as the driver moves. The 20 said plate is provided with two clamping arms, one of which is adapted to impinge against the shuttle near its point, and the other of which is arranged to impinge against the shuttle near its heel, the said clamping-arms being released 25 alternately to permit the loops of needle-thread 30 to pass around the shuttle.

In the drawings, Figure 1 is a sectional side view of a portion of a "Singer" oscillating-shuttle sewing-machine with my invention applied thereto. Figs. 2 and 3 are partial front views of the same, showing the parts in different positions. Fig. 4 is a front view showing the clamping-plate and its operating-cam, the shuttle and driver being removed. Fig. 5 is a 35 detail sectional view of one of the clamping-arms and a portion of the shuttle.

40 A denotes the shuttle-operating shaft, which, in the well-known "Singer" machine, to which my invention is especially applicable, has a rocking or oscillating movement of a little more than half a circle.

45 B is the shuttle-driver, secured to the forward end of the shaft A and having horns b and b', which engage the shuttle C at different points 50 on the latter.

D is a stationary cam, formed, in the present instance, integral with the hanger e, depending

from the bed-plate E, and forming the front bearing for the shaft A.

F is the clamping-plate for the shuttle, provided with the arms f and f', the arm f impinging against the shuttle near the point thereof, and the arm f' engaging the shuttle toward the heel of the latter. The clamping-plate F is pivotally attached to the shuttle-driver by a pin 55 or screw, f'', and is provided with an opening, f', of proper size to receive the stationary cam D.

The shuttle may be held in the carrier by a ring or face-plate, G, as shown in Fig. 1; but this plate will preferably be dispensed with by 60 providing the clamping-arms f and f' with V-shaped lugs f'', adapted to enter V-shaped notches in the shuttle. (See Fig. 5.) This construction will tend to keep the shuttle central in the driver, from which the shuttle cannot escape when in operation, as the centrifugal force will hold the shuttle against the said lugs even when the clamping-arms are loosened to permit the loops of needle-thread to pass. With this construction, a downwardly-extending curved 65 projection, i, on the throat-plate I will be all 70 that will be necessary to securely retain the shuttle in the carrier.

The operation of my invention is as follows: The stationary cam D is so arranged that when 80 the parts are in the position shown in Fig. 2 the clamping-arm f is released from the beak of the shuttle, which has just taken a loop of thread from the needle, so that the said loop 85 can pass around the said beak and between the latter and the forward part of the front horn, b, of the driver, the rear clamping-arm, f', meanwhile firmly holding the body of the shuttle 90 against the inner rear portion of the front horn, b, and also against the inside of the rear horn, b'. As the shuttle continues its movement 95 from the position shown in Fig. 2 to the position shown in Fig. 3, the clamping-arm f' is released and the clamping-arm f is forced against the shuttle-beak, thus firmly grasping 100 the shuttle at its front portion and tilting it clear of the bearings on the horns of the carrier, against which it was previously clamped by the arm f', so that the loop of needle-thread can freely pass around the rear portion of the shuttle. This change of positions of the clamping-arms is effected by the swinging of the clamping-plate F on its pivot-pin, owing to the movement of said plate around the sta-

tionary cam D, this movement of the said plate to change the positions of the arms *f* and *f'* being effected quickly, owing to the form of the cam D, the latter being shaped like an ordinary feed-cam, which gives a sudden movement in a "four-motioned" feed.

It will be seen that my clamping-arms, of which I employ but two, both move bodily with the plate by which they are carried, said arms being preferably formed integral with the said plate, and are consequently rigid therewith. These clamping-arms thus change their positions simultaneously, and when they are respectively in clamping position the shuttle is held so tightly that there is no looseness for the passage of the needle-thread around the part which is clamped, so that the clamping device, in connection with the driver, forms a secure and perfect holder or carrier for the shuttle.

It may be observed that in addition to the great advantage which my invention secures in enabling the shuttle to be run without a race, thus greatly reducing the friction and wear on the shuttle and other parts of the machine, my clamping device holds the shuttle firmly to the driver at the moments when the reverse movements occur, so that the shuttle is prevented from rattling against the driver, and the noise of the machine is thus greatly lessened.

Although I have herein shown my invention as applied to a "Singer" oscillating-shuttle machine, it will be understood that it may be applied to other forms of machines in which the shuttles have either a continuous or reciprocating (or oscillating) rotary movement. It will also be understood that the details of construction may be varied from those herein

shown without departing from the essential features of my invention.

I am aware of the device shown by Patent No. 283,636, to Miller and Diehl, which shows a device by which an oscillating shuttle may be operated without a race for the shuttle to run in, the shuttle being carried by four pivoted levers or arms, which are successively swung outward to let the loop of needle-thread pass. The said arms did not, however, clamp the shuttle, but merely held it loosely, as would be done by an ordinary shuttle-race, and the large number of holding-arms thus rendered necessary caused too much friction and noise to render the device practically unsuccessful.

55 I claim as my invention—

1. The combination, with a movable shuttle-driver and a clamping-plate pivoted thereto, and thus moving bodily therewith, said plate having two clamping-arms adapted to engage the shuttle alternately, of a stationary cam engaging said clamping-plate, and adapted to swing the latter on its pivot to operate the said arms, substantially as set forth.

2. The combination, with the movable shuttle-driver B, having the horns *b* and *b'*, of the clamping-plate F, pivotally attached to the said shuttle-driver and having two arms, *f* and *f'*, and the recess or opening *f'*, and the stationary cam D, arranged to operate said 65 clamping plate, substantially as set forth.

In testimony whereof I affix my signature in presence of two witnesses.

JAMES BOLTON.
